JOHN E. JOHNSON, OF BEAVER FALLS, PENNSYLVANIA, ASSIGNOR OF ONE-HALF TO
EMMET S. BURNS, OF BEAVER FALLS, PENNSYLVANIA.

VACANT-SEAT DETECTOR FOR THEATERS.

1,257,873.

Specification of Letters Patent. Patented Feb. 26, 1918.

Application filed August 16, 1916. Serial No. 115,276.

To all whom it may concern:

Be it known that I, JOHN E. JOHNSON, a citizen of the United States, and a resident of Beaver Falls, in the county of Beaver 5 and State of Pennsylvania, have invented a certain new and useful Improvement in Vacant-Seat Detectors for Theaters, of which the following is a specification.

My present invention relates to signal apparatus and more particularly to apparatus used in open or closed theaters.

The principal objects of my invention are to provide simple and efficient apparatus enabling patrons of theaters to detect vacant 15 seats upon entering the foyer or auditorium of the theater, so that they may be readily accommodated and enabled to quickly, and without confusion, locate the vacant seats most desirable to them; to provide apparatus 20 of the character described which is automatically operated by the person seated or departing so that the services of ushers may be dispensed with; and to provide apparatus of the character described which is 25 economical in the consumption of electrical energy used in connection with the apparatus.

Other objects of my invention will appear in the following detailed description, taken 30 in connection with the accompanying drawings, forming a part of this specification, and in which drawings:—

Figure 1 is a front elevation of a display board forming a part of the apparatus.

Fig. 2 is a diagrammatic view of a portion 35 of the apparatus, showing electrical connections.

Fig. 3 is a central vertical sectional view through a seat showing electrical apparatus 40 in operative relation thereto.

Fig. 4 is an enlarged vertical sectional view through a portion of the display board and showing a shutter in operative relation to one of the perforations thereof.

Fig. 5 is an enlarged sectional view on 45 the line 5—5 of Fig. 4.

In the drawings, where similar characters refer to similar parts throughout the several views, A designates a display board 50 provided with a plurality of perforations B, one for each seat in the theater and arranged according to the seating plan of the theater; C display devices or shutters for said perforations, each preferably carrying 55 delineations signifying the particular aisle

and seat it represents; D mechanism for operating said shutters comprising electro-magnetic means E and mechanical means F; G seats of the theater; H switch mechanism for each seat; J an electric generator, 60 such as a storage battery; and, K illuminating means for display board A.

Referring first to the display board A, it may be made of suitable opaque material, such as sheet metal, wood, or vulcanized 65 fiber, and may carry delineations 21 and 22, representing the numerals for aisles and seats respectively, these delineations applied or affixed to the board preferably with phosphorescent ink or paint, so as to be visible 70 in a darkened space.

The display devices or shutters C are preferably disk-shaped, corresponding in shape to the perforations B and may be pivotally mounted in connection with the 75 board A, as by spindles 23 received by bearings 24 above and below the perforations, each display device or shutter being independently rotatable so as to render their respective perforations in a closed position or 80 an open condition, as is clearly shown in the diagrammatic view in Fig. 2. If desired, each display device may carry delineations 26 signifying the particular aisle 85 and seat it represents.

When the display board is positioned in a darkened portion of the theater, illuminating means 25 is disposed at one side of the display board in a manner to direct the rays therefrom toward the perforations, the 90 board emitting rays wherever the display device or shutters C are so positioned as to render their respective perforations in an open condition.

A suitable mechanism for operating the 95 shutters C, electromagnetic means E, acting in conjunction with subordinate mechanical means F, is provided. The means E may comprise a coil 30 for each device C and a permanent bar magnet 31 rigid with 100 the display device C and oscillatable with its spindle 23. The bar 31 is arranged with respect to the device C that, when the latter is closing its respective perforation, the bar lies parallel to the coil 30. However, if the 105 coil is energized by conducting an electric current therethrough, the bar will quickly swing out of parallel relation to the coil, carrying with it, the display device C.

The mechanical means F may comprise 110

lugs 32 carried by the spindle 23 at opposite sides of the axis thereof; a spring 33 carried by board A, said spring adapted to engage both lugs 32 when its respective display device is in a position rendering the perforation closed; and, an adjusting bolt 34 by which the desired tension may be placed on the spring at its portion engaging the spindle 23 and lugs 32. This means F, for each display device C, is provided to maintain the said device in a position closing its respective perforation when no current is conducted by the coil 30.

Referring now to the switch mechanism H, one switch being provided for each seat of the theater, it comprises a casing 35, preferably of insulation, supported by the frame 36 of the seats, as at 37, clearly shown in Fig. 3 of the drawings; a reciprocable upright 38 extending through casing 35, and carrying a switch point 39; an expansion spring 40 about upright 37 interposed between the head 41 thereof, and the casing 35; and a switch point 41 rigid with casing 35, with which the switch point 39 engages when the upright 38 moves upwardly to its limit, responsive to the action of spring 40. The head 41' of upright 38 engages the under side of seat G so that when said seat is not occupied, switch points 39 and 41 will engage to complete a circuit as hereinafter set forth. When the seat is occupied, it bears down upon upright 38, breaking the circuit at points 39 and 41, and the circuit is so maintained broken so long as the seat is occupied.

The generator J is provided as a source of electrical energy to be conducted through the coils 30 of each display device C. It may also furnish energy for the illuminating means K as clearly shown in the diagrammatic view in Fig. 2. One pole of the generator J is in conducting communication with each switch point 41 as by wires 44, and with one lead of the illuminating means K. The other pole of the generator is in conducting communication with the other lead of illuminating means K, and with each switch point 39, as by wire 45, the coils 31 being interposed in the branches 46 of wire 45.

The operation of the apparatus is as follows:—

Assuming that the theater is partially filled, wherever a seat is occupied, the circuit through switch means H will be broken and the display devices C representing the occupied seats will assume a position, in the example shown, by closing the perforations of the display boards, so as to indicate that they are occupied. A patron upon approaching the board may observe the vacant seats due to the position of such display devices C as are actuated to open their respective perforations, due to the current flowing through their respective coils, the

circuits being completed at the unoccupied seats. If the display devices carry delineations designating the aisle and seats they represent, the illuminating means K will make such delineations clearly visible and a patron may select the desired seat. As soon as the selected seat is occupied, the circuit is broken at its switch means and the particular display device associated therewith moves to a position to indicate that the seat is occupied.

It may not be necessary to bring the apparatus into use when a theater is first opened or while illuminated to an extent where patrons may detect the vacant seats so that there is no consumption of electric energy before or after acts, unless it is desired to display the board in the foyer of the theater. Very little current is required to energize the coils 30, and, since the seats of the theater are usually more than half occupied during business hours, it is preferred to utilize the electric current to designate vacant seats.

Changes in details may be made without departing from the spirit or scope of my invention; but,

I claim:—

1. A vacant seat detector for theaters comprising in combination, a display board provided with a plurality of perforations arranged according to the seating plan of the theater, illuminating means to one side of said display board, shutters for each perforation, each shutter capable of swinging motion to render its respective perforation in a closed condition or an open condition, electro-magnetic means for each shutter to actuate the same rendering its respective perforation in one of the said conditions, and mechanical means for each shutter to actuate the same rendering its respective perforation in the other of said conditions.

2. In a vacant seat detector for theaters, the combination of a plurality of display devices arranged according to the plan of the theater and each carrying delineations signifying the particular seat it represents, said devices capable of movement independently one of another and in one position signifying that its respective seat is occupied, and in another position that such is vacant, electro-magnetic means for each device to maintain, when energized, its respective device in one of the said positions, and mechanical means for each device subordinate to said electro-magnetic means to maintain its respective device in the other of said positions when said electro-magnetic means is not energized.

3. In a vacant seat detector for theaters, the combination of a plurality of display devices arranged according to the plan of the theater, said devices capable of movement independently one of another and in one

position signifying that its respective seat is occupied, and in another position that such is vacant, electro-magnetic means for each device to maintain, when energized, its 5 respective device in one of the said positions, and mechanical means for each device subordinate to said electro-magnetic means to maintain its respective device in the other of said positions when said electro-magnetic 10 means is not energized.

4. In a vacant seat detector for theaters, the combination of a display board provided with a plurality of perforations arranged according to the seating plan of the 15 theater, illuminating means to one side of said display board, a shutter for each perforation, each shutter capable of swinging motion to render its respective perforation in a closed condition or an open condition, 20 electro-magnetic means for each shutter to actuate the same rendering its respective perforation in an open condition, and mechanical means for each shutter to actuate the same rendering its respective perforation 25 in a closed position.

5. In a vacant seat detector for theaters, the combination of a plurality of display devices arranged according to the seating plan of the theater, said devices capable of 30 rotation independently one of another and

in one position signifying that its respective seat is occupied, and in another position that such is vacant, an electric coil for each display device, a permanent bar magnet rigid with each display device adapted to move 35 into and out of parallelism with said coil, mechanical means for maintaining said bar in parallelism with said coil when the latter is not energized and with its respective display device in one of the said positions, and 40 means for energizing said coil.

6. In a vacant seat detector for theaters, the combination of a plurality of display devices arranged according to the seating plan of the theater, said devices capable of 45 rotation independently one of another and in one position signifying that its respective seat is occupied, and in another position that such is vacant, an electric coil for each display device, a magnetic bar adapted to move 50 into and out of parallelism with said coil, lugs at each side of the axis of rotation of each display device and carried thereby, a spring for engagement with said lugs, said lugs arranged relative to said magnetic bar 55 so that when said spring engages both lugs, said bar is in parallelism to said coil, and with said display device in one of said positions, and means for energizing said coil.

JOHN E. JOHNSON.
